UNITED STATES PATENT OFFICE.

WILLIAM LOUDEN, OF FAIRFIELD, IOWA.

COW-STALL

1,057,249.

Specification of Letters Patent.

Patented Mar. 25. 1913.

Application filed October 21, 1909. Serial No. 523,906.

To all whom it may concern:

Be it known that I, WILLIAM LOUDEN, a citizen of the United States, residing at Fairfield, in the county of Jefferson and State of Iowa, have invented a new and useful Improvement in Cow-Stalls, of which the following is a specification.

My invention relates to cow stalls having vertically disposed posts connected to a floor or other supporting means, and having a horizontally disposed top rail attached to the upper ends of the posts in approximately the same horizontal plane, stanchions hung on the top rail between the posts and partitions connected to the posts so as to divide the space on one side of the posts and top rail into separate stalls and permit a cow to occupy each stall and be held therein by means of the stanchions; and it consists of an arrangement of the parts whereby single upright posts will be used in the upper portion and double spaced apart posts will be used in the lower portion of the stalls, the upper ends of the double posts being connected to the lower ends of the single posts while the upper ends of the latter are connected to the horizontal top rail and the upper ends of the partitions are connected to the single posts between their upper and lower ends. Also, of other features which are set forth in this specification and more definitely pointed out in the claims.

The drawing is a perspective of the invention in which—
A is the top rail and D the floor upon which the lower double posts and partitions are mounted.

At the right hand side of the drawing the upper single post is shown by B and the lower double posts by G, G. In the center the upper single post is represented by E and the lower double posts by F while at the left hand side the single post is shown by C and the double posts are designated by I, I.

H represents the partitions which have their lower ends secured to the floor D and their upper ends connected to the single posts B, E and C by means of T shaped clamps J. They are preferably curved so their lower ends will be in an approximately vertical position while their upper ends will be in an approximately horizontal position.

The lower posts G, G, I, I and F have their upper ends bent or inclined toward the lower ends of their corresponding single

posts B, E and C, and are connected thereto by Y shaped clamps L, M and N. The upper ends of the single posts B and E are connected to the top rail A by T clamps J 60 while the upper end of the single post C is connected to the left hand end of the top rail by a corner coupling K. The right hand end of the top rail may be extended any distance desired and additional posts, 65 partitions and stanchions may be connected to it, thus adding any additional number of stalls desired.

While being held in the stalls the cows' heads are placed in the stanchions W which being connected to the top rail at their upper ends and preferably secured at their lower ends to the floor D or to something connected to it, the cows will be securely held in the stalls and yet be free to lie 75 down and get up or turn their heads from side to side. The posts should be made long enough and the top rail raised high enough so that it will not interfere in any way with the free movement of the cows. 80 It should never be lowered to make a railing to stop the forward movement of the cow, this function being performed by the stanchion which is secured to the top rail and preferably also to the floor. 85

Usually a feed trough or manger, which is not shown in the drawing, is placed on the floor at the side of the posts opposite the partitions. If this trough or manger is not used the feed which generally consists 90 principally of hay or other forage is placed on the floor where the manger would be placed if used. As cow stalls have generally been constructed a single vertical post reaching from the floor to the top rail has been 95 set so as to connect with each partition H. This is a desirable construction so far as giving the cow plenty of freedom to move her head from side to side is concerned but it does not form an efficient guard to prevent the hay or other feed in the manger or on the floor from getting under the cow's feet. 100

The principal advantage of my invention is that while it forms a better guard for the feed at the bottom it affords the cow while she is standing and needs it most, all the freedom she would have if only a single post were used. The drawing may not be in the proper proportions, but if not, this can be easily adjusted in actual use, so the double posts while affording sufficient protection for

the feed will not extend up so far as to interfere with the freedom of the cow. Also the partitions H may be set lower if found best without departing from the spirit of 5 my invention.

The stall is neat in appearance or may easily be made so and it will be easily kept in a clean sanitary condition. There are no cracks or crevices or pockets to catch and 10 hold dirt nor any sharp angular corners to irritate or injure the cow. The stall is inexpensive yet strong and durable and there is little or no obstruction of light which is an important feature in the equipment of a 15 dairy barn. In addition to this my invention has the advantages of two posts in the lower half of the stall and also the advantages of a single post in the upper half of the stall while it avoids the disadvantages 20 of a single post in the lower half of the stall and of two posts in the upper half of the stall.

What I claim is:—

1. In cow stalls, a horizontally disposed 25 top rail supporting stanchions thereon, upright members connected to said top rail between the stanchions and extending part way down toward a support below and vertically disposed posts inserted in said support on each side of said members and having their upper ends bent toward each other at an angle and connected to the lower ends of the members.
2. In cow stalls, a horizontally disposed 30 top rail extending in the same plane throughout its length and supporting stanchions thereon, upright members connected to said top rail between the stanchions and extending part way down toward a support below and vertically disposed posts inserted in said support on each side of said

members in line therewith and having their upper ends bent toward each other at an angle and connected to the lower ends of the members.

3. In cow stalls, a horizontally disposed top rail extending in the same plane throughout its length and supporting stanchions thereon, upright members connected to said top rails between the stanchions and extending part way down toward a support below, vertically disposed posts inserted in said support on each side of said members and having their upper ends bent toward each other at an angle and connected to the lower ends of the members and partition posts having their upper ends connected to the upright members above their connections with the supporting posts and their lower ends attached to the stable 60 floor.

4. In cow stalls having a horizontal top-rail, single vertically disposed posts connected at intervals to the lower side of the top-rail, partitions connected to the vertical posts 65 so as to divide the space on one side into stalls, and a stanchion connected to the top rail approximately half way between the posts and stall partitions, in combination with a series of pairs of vertically disposed 70 posts spaced apart and set in the lower part of the stall in line with the top rail, and each pair having their upper ends bent toward each other and connected to the lower ends of the single posts at a point a distance below the top rail.

Fairfield, Iowa, October 19, 1909.

WILLIAM LOUDEN.
